ABSTRACT OF THE DISCLOSURE

Novel compounds having the following formula:

wherein R' and R'' are the same or different and represent an alkyl group having up to 18 carbon atoms, an alkenyl group having up to 18 carbon atoms, an aryl group having up to 10 carbon atoms, an aralkyl group having up to 10 carbon atoms, or a cycloalkyl group having up to 10 carbon atoms; wherein R₁ represents hydrogen, an alkyl group having up to 6 carbon atoms, an aryl group having up to 10 carbon atoms or

wherein R₂ and R₃ are the same or different and each represents an alkyl group having up to 6 carbon atoms or a phenyl group or when taken together R₂ and R₃ represent an alkylene or oxyalkylene group having 4 or 5 carbon atoms.

This is a division of our co-pending application Ser. No. 627,289, filed Mar. 31, 1967, now Pat. No. 3,538,147.

This invention relates to novel 3-butene-1,2-dicarboxylic acid esters. More particularly this invention relates to 3-butene-3-carbamoyl-1,2-dicarboxylic acid esters and 3-butene-3-carbonyl-1,2-dicarboxylic acid esters.

It has been found that novel butene polycarboxylic acid esters can be manufactured by reacting an acrylic compound selected from the group consisting of acrolein, vinyl ketones and N,N-disubstituted acrylic amides with an ethylene dicarboxylic acid ester selected from the group consisting of maleic acid esters and fumaric acid esters in the presence of an organic tertiary phosphorus (III) compound selected from the group consisting of tertiary phosphines and tertiary phosphoamides.

The novel compounds of this invention have the following formula:

wherein R' and R'' are the same or different and represent an alkyl group having up to 18 carbon atoms, an alkenyl group having up to 18 carbon atoms, an aryl group having up to 10 carbon atoms, an aralkyl group having up to 10 carbon atoms; or a cycloalkyl group having

2

up to 10 carbon atoms; wherein R₁ represents hydrogen, an alkyl group having up to 6 carbon atoms, e.g., methyl, ethyl, propyl, isopropyl, butyl, n-pentyl, and n-hexyl and preferably methyl, an aryl group having up to 10 carbon atoms, e.g., phenyl and naphthyl, or

15 wherein R₂ and R₃ are the same or different and each represents an alkyl group having up to 6 carbon atoms or a phenyl group or when taken together R₂ and R₃ represent an alkylene or oxyalkylene group having 4 or 5 carbon atoms.

20 It is a principal object of the invention to provide novel 3-butene-1,2-dicarboxylic acid esters.

It is a further object of this invention to provide novel 3-butene-3-carbamoyl-1,2-dicarboxylic acid esters.

It is a still further object of this invention to provide novel 3-butene-3-carbonyl-1,2-dicarboxylic acid esters.

It is a still further object of this invention to provide compounds which are useful as starting materials in polymerization reactions.

30 Other objects and advantages of the novel compounds of this invention will become more apparent from the following more detailed description thereof.

Specific examples of the novel 3-butene-3-carbonyl-1,2-dicarboxylic acid esters of this invention include the following compounds:

1,2-dimethoxycarbonyl-3-acetyl butene-3,
1,2-diethoxycarbonyl-3-acetyl butene-3,
1,2-dimethoxycarbonyl-3-formyl butene-3,
40 1,2-diethoxycarbonyl-3-formyl butene-3,
1,2-diallyloxycarbonyl-3-formyl butene-3,
1,2-dimethoxycarbonyl-3-benzoyl butene-3,
1,2-diallyloxycarbonyl-3-benzoyl butene-3,
1,2-dicyclohexyloxycarbonyl-3-benzoyl butene-3, etc.

45 The novel 3-butene-3-carbamoyldicarboxylic acid esters of this invention include the following compounds:

1,2-dimethoxycarbonyl-3-dimethylcarbamoyl butene-3,
1,2-diethoxycarbonyl-3-diethylcarbamoyl butene-3,
1,2-dimethoxycarbonyl-3-dimethylcarbamoyl butene-3,
50 1,2-di-n-butoxycarbonyl-3-di-n-butylcarbamoyl butene-3,
1,2-dimethoxycarbonyl-3-(N-methyl-N-n-butyl) carbamoyl butene-3,
1,2-dimethoxycarbonyl-3-(N-methyl-N-n-butyl) carbamoyl butene-3,
1,2-dimethoxycarbonyl-3-(N-methyl-N-phenyl) carbamoyl butene-3,
55 1,2-dimethoxycarbonyl-3-(N-methyl-N-phenyl) carbamoyl butene-3,
1,2-dimethoxycarbonyl-3-(N-methyl-N-phenyl) carbamoyl butene-3,
1,2-dimethoxycarbonyl-3-morpholinocarbonyl butene-3,
1,2-diethoxycarbonyl-3-morpholinocarbonyl butene-3,
60 1,2-dimethoxycarbonyl-3-piperidinocarbonyl butene-3,
1,2-diethoxycarbonyl-3-piperidinocarbonyl butene-3,
1,2-dimethoxycarbonyl-3-piperidinocarbonyl butene-3,
1,2-dicyclohexyloxycarbonyl-3-piperidinocarbonyl butene-3,
1,2-dimethoxycarbonyl-3-piperidinocarbonyl butene-3,

3

1,2-diallyloxycarbonyl-3-dimethylcarbamoyl butene-3 and 1,2-diphenoxycarbonyl-3-diethylcarbamoyl butene-3, etc.

Of the above compounds, 1,2-dimethoxycarbonyl-3-formyl-butene-3, 1,2-diethoxycarbonyl-3-formyl-butene-3, 1,2-dimethoxycarbonyl-3-acetyl butene-3 and 1,2-diethoxycarbonyl-3-acetyl butene-3 are preferred.

The novel 3-butene-1,2-dicarboxylic acid esters of the present invention can be utilized as starting materials for the production of polymers. In particular, by copolymerizing the compounds of this invention with a monomer, such as styrene, acrylonitrile, acrylic acid, acrylic esters, methacrylic acid, methacrylic esters and vinyl acetate, the impact strength and adhesive property of the resultant copolymer is improved. When the compounds of this invention are converted to their acid anhydrides, they are useful as curing agents for epoxy resins and the like. The tendency for easy decarbonization of these compounds also makes them useful as blowing agents.

The novel 3-butene-1,2-dicarboxylic acid esters of this invention can be produced by reacting an acrylic compound of the formula:

(wherein R_1 has the meaning as already defined above) with a maleic acid ester of the formula:

(wherein R' and R'' have the meaning as already defined above) or a fumaric acid ester of the formula:

(wherein R' and R'' have the meaning as already defined above) in the presence of a catalytic amount of an organic tertiary phosphorus (III) compound selected from the group consisting of tertiary phosphines and tertiary phosphoamides.

Examples of starting acrylic compounds of Formula II, which are known in chemical literatures, are as follows:

Acrolein; vinyl alkyl ketones such as vinyl methyl, vinyl ethyl, vinyl propyl, vinyl butyl, vinyl pentyl and vinyl hexyl ketone; and vinyl aryl ketones such as vinyl phenyl, vinyl tolyl, vinyl p-methoxy phenyl, vinyl p-chlorophenyl and vinyl naphthyl ketone; and N,N -di-substituted acrylamide such as the following N,N -dialkyl substituted acrylamide compounds: N,N -dimethyl, N,N -diethyl, N,N -di-propyl, N -methyl- N -ethyl, N,N -dibutyl, N,N -dipentyl and N,N -dihexyl acrylamide, N,N -diaryl substituted acrylamide such as N,N -diphenyl, N,N -ditolyl, N,N -di-(p-methoxy phenyl), N,N -di-(p-chloro-phenyl), N -methyl- N -phenyl, acryloyl morpholine and acryloyl piperidine, etc.

The maleic acid esters and fumaric acid esters to be reacted with the acrylic compound of the Formula II include the following:

The dialkyl maleates or fumarates such as dimethyl, diethyl, dipropyl, dibutyl, dipentyl, diheptyl, dioctyl, dinonyl, didecyl, didodecyl, diheptadecyl, dioctadecyl, methyl ethyl, methyl butyl, and ethyl butyl maleate or fumarate; the dialkyl maleates or fumarates such as divinyl, diallyl, diisopropenyl maleates or fumarates; diaryl maleates or fumarates such as diphenyl, ditolyl, di(p-methoxyphenyl), di-(p-chlorophenyl), phenyl-tolyl, and phenyl-p-chlorophenyl maleates or fumarates; the diaryl maleates or fumarates such as dibenzyl, diphenylethyl, and benzyl phenylethyl maleates or fumarates; the dicycloalkyl maleates or fumarates such as dicyclopentyl, dicyclohexyl and cyclopentyl-cyclohexyl maleates or fumarates, etc.

4

The organic tertiary phosphorus (III) compound used as the catalyst is selected from the group consisting of tertiary phosphines and tertiary phosphoamides which have the following formula:

wherein R_4 , R_5 and R_6 are the same or different and represent an alkyl group having up to 8 carbon atoms which alkyl group may have a cyano, carbonyl, hydroxy, hydroxycarbonyl or alkoxy carbonyl group having up to 9 carbon atoms substituted thereon, a cycloalkyl group having 5 to 8 carbon atoms, an aryl, preferably phenyl; any two of R_4 , R_5 and R_6 may form a hetero ring together with the phosphorus atom,

wherein R_7 and R_8 are the same or different and represent an alkyl group having up to 8 carbon atoms, a cycloalkyl group having 5 or 6 carbon atoms, an aryl group, preferably a phenyl group, or R_7 or R_8 together represent an alkylene or oxyalkylene having 4 or 5 carbon atoms or

wherein R_9 and R_{10} are the same or different and represent an alkyl group preferably having up to 8 carbon atoms, a cycloalkyl having 5 or 6 carbon atoms or any aryl group, preferably a phenyl group.

Examples of the tertiary phosphines useful as catalysts for producing the novel compounds of this invention are: trialkyl phosphines such as trimethyl, triethyl, tripropyl, triisobutyl, tributyl, trihexyl and trioctylphosphine; tricycloalkyl phosphines such as tricyclopentyl, tricyclohexyl, and cyclopentyl dicyclohexyl phosphine; triarylphosphines such as triphenyl phosphine; alkyl diaryl or dialkyl aryl phosphines such as isobutyl diphenyl diisobutyl phenyl, 4-hydroxy butyl diphenyl and phenyl diethylphosphine; alkyl dicycloalkyl or dialkyl cycloalkyl phosphines such as ethyl dicyclohexyl, diethyl cyclohexyl, butyl dicyclohexyl dibutyl cyclohexyl, dicyclohexyl-2-cyanoethyl, cyclohexyl-di-(2-cyanoethyl), dicyclohexyl-2-methoxycarbonyl-ethyl, cyclohexyl-di-(2-hydroxycarbonyl) and dicyclohexyl-2-butyroyl phosphine; and tertiary phosphines such as compounds having the following formulae:

Examples of the tertiary phosphoamides are tris (dimethylamino) phosphines such as tris (dimethylamino), tris (diethylamino), tris (diisopropylamino) tris (dibutylamino) and tris (diisobutylamino) phosphine, tris (dicy-

cloalkylamino) phosphines such as tris (dicyclopentylamino), tris (dicyclohexylamino) phosphine and the like, tris (diaryl amino) phosphines such as tris (diphenylamino) a tris(ditolyl amino) and tris (di-p-chlorophenylamino) phosphine, tertiary phosphoamides wherein R₇ and R₈ together form an alkylene or oxyalkylene group having 4 or 5 carbon atoms such as trimorpholino, tri-piperidino and tripyrrolidino phosphine, tertiary phosphoamides having different substituents such as tris (N-methyl-N-phenylamino) tris (N-methyl-N-ethylamino), tris (N-ethyl-N-cyclohexylamino), tris (N-phenyl-N-cyclohexylamino), methyl dimorpholino, ethyl dimorpholino, cyclo hexyl dipyrrolidino, phenyl dipyrrolidino and diphenyl morpholino phosphine; and tertiary phosphines wherein R₄, R₅ and R₆ are

such as tetracyclohexyl diphosphine, tetradiisobutyl phosphine, tetrabutyl phosphine and butyl tricyclohexyl phosphine.

Also suitable as catalysts in the process of the invention are catalysts wherein the tertiary phosphine moiety is contained within a metal complex, such as a modified metal carbonyl complex of a transition metal.

Especially preferably among the above-mentioned organic tertiary phosphorus (III) compounds are tertiary phosphines wherein a secondary carbon atom is linked with a phosphorus atom, such as tertiary phosphine having a cycloalkyl group such as tricyclopentyl phosphine, tricyclohexyl phosphine, tricycloheptyl phosphine, tris (methylcyclohexyl) phosphine, tricycloctyl phosphine, trinorbornyl phosphine, butyl dicyclohexyl phosphine, ethyl di-cyclohexyl phosphine, diethyl cyclohexyl phosphine and dibutyl cyclohexyl phosphine and tertiary phosphoamides wherein R₇ and R₈ have 3 to 8 carbon atoms such as tris (dialkyl amino) phosphine such as tris (di-n-butylamino) phosphine and tris (di-isobutylamino) phosphine.

In this invention, the amount of ethylene dicarboxylic acid ester can be determined according to the amount used in an ordinary stoichiometrical reaction, and is in general 0.1 to 5 mole equivalents, preferably 0.3 to 1.5 mole equivalents, based on the acrylic compound.

The reaction of this invention proceeds in the presence of the organic tertiary phosphorus (III) compound in a catalytic amount or in an amount of 0.0001 to 0.1 mole equivalent based on the acrylic compound but does not proceed in its absence. The amount can be increased optionally.

The reaction temperature is ordinarily 0 to 200° C., and preferably 30 to 120° C.

A polymerization inhibitor such as tert.-butylpyrocatechol and pyrohydroquinone may also be added to the reaction system.

It is also preferable that the atmosphere of the reaction system should be non-oxidizing.

The use of an inert solvent is not necessary, but the following solvents can be used with good results: Ethers such as dimethyl and diethyl ether, dioxane, tetrahydrofuran, alcohols such as ethyl, isopropyl, tert.-butyl alcohol, sec.-butyl, sec.-amyl, tert.-amyl, octyl and decyl alcohol, aromatic hydrocarbons such as benzene, toluene and xylene, and compounds with a nitrogen-containing organic base such as dimethyl formamide, pyridine, triethyl amine and trimethyl amine.

When the reaction of this invention has sufficiently proceeded, the organic tertiary phosphorus (III) compound may be inactivated by addition to the reaction system of a catalyst-inactivating agent such as adipic acid and p-toluenesulfonic acid.

The method of this invention also includes an embodiment wherein 3-butene-3-N-substituted carbamoyl-1,2-dicarboxylic acid ester can be converted into 3-butene-1,2,3-tricarboxylic acid by heating in an acid or alkali aqueous solution for hydrolysis.

3-butene-polycarboxylic acid ester can be converted to 3-butene-polycarboxylic acid ester having other ester group by heating in an alcohol in the presence of an ester-interchange catalyst such as sulfuric acid. 3-butene tricarboxylic acid or its esters can be converted into 3-butene polycarboxylic acid or its esters by reduction with hydrogen gas in the presence of a reducing catalyst such as nickel and palladium. These 3-butene-tricarboxylic acids or their esters find wide applications as plasticizers, enamels for electric wires and water-soluble paints. If 3-butene-1,2,3-tricarboxylic acid is heated to about 200° C., it can be converted to dimethylmaleic anhydride.

The following examples illustrate the preferred embodiments of the novel compounds of this invention only and should not be taken as limiting.

EXAMPLE 1

A solution of 3.0 g. of acrolein, a polymerization inhibitor and 150 g. of dioxane was added dropwise to a well-stirred solution of 15 g. of diethyl fumarate and 0.6 g. of tricyclohexyl phosphine in an atmosphere of nitrogen at room temperature. After the reaction mixture was stirred for 9 hours, a small amount of adipic acid was added to stop the reaction. The mixture was distilled to remove the solvent and 2.5 g. of 1,2-diethoxycarbonyl-3-formyl butene-3 were isolated by rectification.

EXAMPLE 2

A solution of 6 g. of methyl vinyl ketone, a polymerization inhibitor and 50 g. of dioxane was added dropwise to a well-stirred solution of 10 g. of diethyl fumarate and 0.7 g. of tricyclohexyl phosphine in an atmosphere of nitrogen at room temperature. After the reaction mixture was stirred continuously overnight, the reaction was stopped by adding a small amount of adipic acid. The dioxane was distilled off and 11.5 g. of 1,2-diethoxycarbonyl-3-acetyl butene-3 was isolated by rectification.

EXAMPLE 3

A solution of 5.2 g. of methyl vinyl ketone, a polymerization inhibitor and 100 g. of dioxane was added dropwise to a well-stirred solution of 19 g. of dimethyl fumarate and 0.6 g. of tricyclohexyl phosphine in a nitrogen atmosphere at room temperature. After stirring the reaction mixture for 10 hours, a small amount of adipic acid was added to stop the reaction. The dioxane was distilled off and 13.8 g. of 1,2-dimethoxycarbonyl-3 acetyl butene-3 was isolated by rectification.

EXAMPLES 4-14

A solution of a vinyl ketone derivative containing a polymerization inhibitor was added dropwise with good stirring to a solution containing either a fumaric acid ester of a maleic acid ester and a catalyst in an atmosphere of nitrogen at a predetermined temperature. The reaction mixture was stirred for a predetermined length of time and a small amount of adipic acid was added to the reaction mixture. The solvent was removed by distillation and the reaction product was isolated by rectification. Results are shown in Table I in which Me=methyl, Et=ethyl and ph=phenyl.

EXAMPLES 15-24

A pressure bottle was charged with an acyclic amide derivative, either a fumaric acid ester or a maleic acid ester, a catalyst, a polymerization inhibitor and a solvent and maintained at the temperature indicated in Table II. A small amount of adipic acid was added to the reaction

mixture, and the solvent and impurities were removed by distillation of 2-dialkoxycarbonyl-3-butene-2 and -butene-3. The products obtained are shown in Table II, in which

represents a morpholino formed together with the adjacent nitrogen atom, and

represents a piperidino formed with the adjacent nitrogen atom, and Bu represents n-butyl.

What is claimed is:

1. A 3-butene-1,2-dicarboxylic acid ester of the formula:

wherein R' and R'' are the same or different and are selected from the group consisting of an alkyl group having up to 18 carbon atoms, and hydrocarbon aralkyl group having up to 10 carbon atoms, and a cycloalkyl group having 5 or 6 carbon atoms; wherein R₁ is selected from the group consisting of hydrogen, an alkyl group having up to 6 carbon atoms, and a hydrocarbon aryl group having up to 10 carbon atoms.

2. A butene polycarboxylic acid ester according to claim 1 wherein said ester is 1,2-dimethoxycarbonyl-3-acetyl butene-3.

3. A butene polycarboxylic acid ester according to claim 1 wherein said ester is 1,2-diethoxy carbonyl-3-acetyl butene-3.

4. A butene polycarboxylic acid ester according to claim 1 wherein said ester is 1,2-dimethoxycarbonyl-3-formyl butene-3.

5. A butene polycarboxylic acid ester according to claim 1 wherein said ester is 1,2-diethoxycarbonyl-3-formyl butene-3.

6. A butene polycarboxylic acid ester according to claim 1 wherein said ester is 1,2-dimethoxycarbonyl-3-benzoyl butene-3.

7. A butene polycarboxylic acid ester according to claim 1 wherein said ester is 1,2-dicyclohexyloxycarbonyl-3-benzoyl butene-3.
